DESIGN FOR A PAPER DISH

Robert E. Rutledge, Kalamazoo, Mich., assignor to Sutherland Paper Company, Kalamazoo, Mich.

Application April 16, 1934, Serial No. 51,420

Term of patent 14 years

To all whom it may concern:

Be it known that I, ROBERT E. RUTLEDGE, a citizen of the United States, residing at Kalamazoo, in the county of Kalamazoo, and State of Michigan, have invented a new, original, and ornamental Design for Paper Dishes, of which the following is a specification, reference being had to the accompanying drawing, forming part thereof:

Fig. 1 is a plan view;
Fig. 2 is an elevation, and
Fig. 3 is a central vertical section on a line corresponding to line 3—3 of Fig. 1, of a paper dish, showing my new design.

I claim:

The ornamental design for a paper dish, as shown.

ROBERT E. RUTLEDGE.
